Attorney.

UNITED STATES PATENT OFFICE.

ARTHUR L. ADAMY, OF REED CITY, MICHIGAN.

RAILROAD TIE.

Application filed April 11, 1927. Serial No. 183,678.

This invention relates to a railroad tie and is more particularly concerned with a composite tie of steel and concrete. It is an object and purpose of the present invention to provide a tie made of steel and concrete in such a manner that the concrete supporting portions of the tie are in sections so as to permit the necessary flexing of the tie under the weight of a train passing thereover and the concrete does not rupture but keeps its form at all times. A tie of this character is durable, lasting almost indefinitely, while the flexing of the tie permits better construction, and insures that the rolling stock of the railroad is not jarred and damaged as it would be in a completely rigid road bed.

For an understanding of the invention reference may be had to the following description taken in connection with the accompanying drawing, in which,

Fig. 1 is a perspective view of the tie of my invention, rails being shown as attached thereto.

Fig. 2 is an elevation of the tie, parts of the structure being broken away and shown in section for better disclosure, and

Fig. 3 is a somewhat enlarged transverse section through the tie.

Like reference characters refer to like parts in the different figures of the drawing.

In the construction of the tie a metal member or bar, the full length of a tie is used preferably of channel form having a web 1 with the flanges 2 depending therefrom. Underneath this bar a series of concrete blocks 3 are located in alignment, each having a narrower section 4 at its upper side to fit within the channel bar as shown in Figs. 1 and 3. The base portions of the blocks may be widened as much as is necessary in order to provide the required bearing surface.

The blocks are spaced apart short distances at their contiguous ends and are secured to the channel in any suitable manner. I have shown a bolt 5 having a head 6 embedded in each concrete block, the bolt passing upwardly through the web 1 of the channel and having a nut 7 threaded onto its upper projecting end. It is necessary only to make a connection of this kind sufficient to hold the blocks in relation to the channel bar until such time as the ties are placed in the road bed.

Preferably between the adjacent ends of

the blocks, fillers 8 of elastic material, such as asphalt or the like, are placed, the same being of material like that used for expansion joints in building of concrete roads. 60

The rails 9 shown in Fig. 1 lie above the ties and in practice the lower flanges of the rails are received in a chair 10. Retaining plates 11 extend from the side portions of the chair over the flanges of the rail, all 65 being tightly secured together by means of bolts 12 which pass upwardly through the web 1 of the channel, through said chair and the plates 11.

The tie as constructed with the sectional 70 concrete base blocks has sufficient bearing surface at its under side to carry the weight of trains passing over, yet is capable of yielding under the pressure of the weight of the trains. By reason of the gaps between the blocks 3 such yielding does not result in any cracking or rupture of the concrete as any opening made by the yielding of the tie will take place at said gaps. The expansion joint material indicated at 8 is 80 compressible and expandable a limited amount and does not interfere in any way with the requisite yielding of the tie. The construction is simple to produce, the cost is relatively low compared to ties of similar 85 character and the durability of the same is especially good. Although the structure as described and shown in the drawing provides for spaced apart blocks with elastic filler between them, it is not essential that 90 the device be so constructed. The blocks may be spaced a short distance apart and no elastic filler provided or the blocks may be placed closely together. In either of 95 these structures the tie will be operative and the elementary feature of the invention will be present.

It is to be understood that the cross sectional shape of the blocks may be varied from the rectangular shape shown and described, for instance the blocks may be widened at the base to provide a greater bearing surface.

The invention is defined in the appended claim and is to be considered comprehensive 105 of all forms of structure coming within its scope.

I claim:

A railroad tie comprising a metal bar extending the full length of the tie and arranged at the top thereof, a plurality of concrete blocks located underneath the said 110

bar and arranged in alignment with their adjacent ends spaced short distances apart, means for securing the blocks and the bar together, and fillers of plastic elastic material located in the spaces between the concrete blocks and being of substantially uniform area with the ends of the blocks and

forming expansion joints between the blocks to permit the cross tie to yield without rupture.

10

In testimony whereof I affix my signature.

ARTHUR L. ADAMY.
